HEATING FEED WATER

Neal T. McKee, Bronxville, N. Y., assignor to The
Superheater Company, New York, N. Y.

Application April 24, 1936, Serial No. 76,296

18 Claims. (Cl. 122—442)

This application is a continuation in part with respect to my co-pending application Serial No. 455,022 filed May 23, 1930 and is to be considered as relating back to said application Serial No. 5 455,022 with respect to all common subject matter.

My invention relates to the supplying of pre-heated feed water to boilers and has particular reference to the feeding of locomotive boilers.

In order to increase the thermal efficiency of 10 locomotives the feed water supplied thereto is now generally preheated, the source of heat for this purpose being exhaust steam from the locomotive engine, and in some instances also from the several steam driven auxiliaries with which 15 the locomotive is equipped. Heretofore this pre-heating of the feed water has been accomplished by either of two general types of apparatus, i. e., by means of an injector operated largely by engine exhaust steam when such steam is available, and operated by live steam when exhaust steam is not available, or by means of a feed water heater of either the closed or open type, used in conjunction with some form of mechanical feed pump. Neither of these general forms of equipment 20 is completely satisfactory from all standpoints because of inherent limitations which render them in one or more respects unsuitable for the work they are intended to perform. For example, it is desirable to preheat the feed water 25 going to the boiler to the maximum possible degree, but this factor in the case of the exhaust steam injector must be subordinated to the primary requirement of securing with the injector a delivery pressure sufficient to force water to the 30 boiler. In order to secure such a delivery pressure under any set of locomotive operating conditions which may exist, the injector must be designed primarily to produce pressure and in order to secure this result the injector design does not permit the water to be heated to a degree which 35 might be reached if heating of the water were the only factor which had to be considered in the design. Furthermore, it is difficult to secure continued and uninterrupted operation of an exhaust steam injector when the latter has to deliver against the high boiler pressures now in common use, and when unfavorable operating conditions exist it is sometimes impossible to 40 secure proper operation of this type of apparatus.

The systems using pumps and feed water heaters also possess certain limitations of a practical nature which render them not wholly desirable. In addition to the undesirable weight necessary in a heater of desired capacity, the 45 feed water heaters are subject to many practical

difficulties due to leakage, scaling, relatively heavy weight and other defects which need not here be discussed in detail.

The present invention has for its general purpose the provision of means for supplying pre-heated feed water which will retain the advantages of systems heretofore developed, while at the same time eliminating to the greatest possible extent the disadvantages inherent in prior systems. The invention further contemplates 5 the provision of means whereby the temperature of the boiler feed water may be heated to a degree materially above the temperature of the exhaust steam from the main engine, such additional heating being accomplished in a thermally efficient manner. More specifically, the invention contemplates the use of an injector capable of delivering feed water by the condensing action of the exhaust steam against a pressure substantially 10 above atmospheric but materially lower than boiler pressure, said injector being designed primarily as a feed water heating means and only secondarily as a pressure elevating means. By utilizing the injector in this manner it may be readily designed to secure the maximum possible 15 heating effect from the exhaust steam and furthermore it may be designed so that it will operate under the most adverse conditions encountered 20 in locomotive practice, for example, in cases where the temperature of the water supplied to the injector is relatively high and with exhaust steam being supplied to the injector under widely varying 25 pressures. In accordance with the invention, water delivered from the injector is supplied to some form of mechanical pumping means which 30 raises the pressure of the water as delivered from the injector and forces it to the boiler. Preferably such pumping means is steam driven and in case such apparatus is used, the exhaust steam from the pump driving element is utilized to secure an additional heating effect. This is accomplished by condensing the exhaust steam 35 from the pump driving element with the water delivered by the injector, this supply of steam being maintained, through the use of suitable back pressure means, under a pressure materially 40 above atmospheric, and therefore at a higher temperature than the exhaust steam with which the feed water is initially heated in the injector.

By means of the above general arrangement the form of injector necessary can be considerably simplified as compared with the ordinary exhaust steam injector and this relatively light and simple apparatus can be substituted for the heavy and cumbersome feed water heater now ordinarily 45

employed in conjunction with the boiler feed pump.

Other important advantages with respect to installation, control, etc., are secured through this combination of elements and for a clearer understanding of the invention and the various advantages accruing from its use, reference may best be had to the accompanying diagrammatic drawings of suitable forms of apparatus embodying the invention, and the ensuing detailed description thereof.

In the drawings:

Fig. 1 is a diagrammatic side elevation, partly in section, of apparatus embodying the invention;

Fig. 2 is a view similar to Fig. 1, showing apparatus similar to that shown in Fig. 1 but provided with a different control arrangement; and

Fig. 2a is a plan view of part of one of the controls shown in Fig. 2.

Referring now to Fig. 1 of the drawings, A represents an exhaust steam injector supplied through conduit B with feed water which is delivered from the injector through conduit C, surge tank D and conduit E to the pump F, and from the latter through conduit G to the boiler check valve (not shown).

The specific details of the injector A form no part of the present invention, but by way of illustration a modified form of the type of exhaust steam injector disclosed in U. S. Patent No. 1,618,135, granted to me on February 15, 1927, is illustrated, said injector comprising a main casing 1 forming a low pressure steam chamber 2 from which steam is delivered to the main steam nozzle 3, the latter being located in alignment with a water nozzle or cone 4 supplied with water from chamber 5 which is connected by means of passage 6 with the water supply conduit B. Water valve 7 controls the admission of water to the injector, this valve being opened by means of piston 8 actuated upon the admission of steam thereto through the control pipe 9.

The steam and water mixture from the water cone 4 enters a combining tube of usual form (not shown) and passes by way of the delivery tube 10 to chamber 11, which communicates with the delivery conduit C. The combining tube chamber 12 of the injector communicates by way of valve 13 with the usual overflow outlet 14. Valve 13 is normally held closed during periods when the injector is operated by means of piston 15, which is in communication with the delivery chamber 11, and valve 13 furthermore may be manually closed by means of the control mechanism indicated generally at H and comprising a manually operable member located at the point from which the injector is controlled.

The amount of water delivered by the injector is controlled by longitudinal movement of the main steam nozzle 3, which movement it will be observed will restrict or enlarge the annular opening through which water is delivered from the passage 6 to the water cone 4. Movement of nozzle 3 may be conveniently effected by means of a rotatable eccentric member 16 connected by any form of connection, such as the universally mounted shaft 17, to a main control lever 18, the latter being located at the point of control for the apparatus.

Exhaust steam for operating the injector when the power plant engine is running and for pre-heating the feed water is supplied through the exhaust steam pipe 19 by way of the exhaust valve 20 to the main chamber 2 of the injector.

Since it is necessary to be able to operate the in-

jector during periods when exhaust steam is not available means are provided for supplying, in lieu of the exhaust steam, live steam at reduced pressure which hereinafter will be referred to as auxiliary steam. The auxiliary steam can be advantageously taken from the high pressure steam pipe 9 through a suitable branch 9a which communicates with chamber 2 by way of passage 21, said passage being controlled by the automatic or change over valve 22.

In order to secure the uninterrupted operation of the injector, means are provided for automatically opening and closing valves 20 and 22 in alternation so that chamber 2 may be supplied either with exhaust steam from pipe 19 or with auxiliary live steam from pipe 9. Numerous specific forms of apparatus are known by which this function may be accomplished. For purposes of illustration I have shown a form of apparatus disclosed in detail in U. S. Patent No. 1,870,006, granted August 2, 1932, on the application of Malcolm Hard. A brief description of this apparatus follows: Valve 22 is provided with a piston-like head 22a mounted in cylinder 23, the form of the valve being such that when pressure is present in cylinder 23, valve 22 will be closed by pressure of steam admitted to it through branch pipe 9a and when pressure is relieved from cylinder 23, valve 22 will be lifted to open position by the pressure of steam from pipe 9a. Steam is admitted to and exhausted from cylinder 23 through passage 24, the latter being either placed in communication with a zone of low pressure or with a supply of high pressure steam by means of the double-seated relay valve 25 operated by piston 26. The position of piston 26 is in turn controlled by the presence or absence of pressure in cylinder 27 in which steam pressure will be built up by leakage past piston 26, provided that the vent pipe 28 is closed. This vent pipe is controlled by a needle valve 29 operated by diaphragm 30, the latter being placed in communication with the exhaust passages of the main engine through pipe 31.

Passage 24 communicates by way of passage 32 with cylinder 33, in which is mounted piston 34, the latter operating on the admission of steam to cylinder 33 to open valve 20 against the action of spring 35 which tends to hold the exhaust valve in closed position. The operation of this part of the apparatus is as follows: If exhaust steam is available for use in the injector, pressure will be transmitted through pipe 31 to diaphragm 30, thereby closing the needle valve 29 and permitting steam pressure to build up in cylinder 27. Pressure in this cylinder will force piston 26 to the position shown, causing valve 25 to close communication between passage 24 and the vent pipe 36 and establish communication between passage 24 and passage 37 leading from the steam supply branch 9a. This permits steam to flow from 37 by way of 24 to cylinder 23 to close the automatic valve 22. At the same time steam under pressure is supplied through passage 32 to piston 34 and the exhaust valve 20 is opened. If the exhaust steam supply fails due to closure of the engine throttle the release of exhaust steam pressure from diaphragm 30 permits the needle valve to open and vent cylinder 27 through pipe 28, and piston 26 becomes unbalanced and shifts valve 25 to its lower position, cutting off communication between passages 24 and 27 and establishing communication between passage 24 and the vent pipe 36. Pressure is thereby released from cylinder 23 and also from the exhaust valve cylinder 33, 75

causing the automatic valve 22 to be lifted by steam pressure from branch 9a and permitting the exhaust valve to be closed by spring 35. The pressure of the auxiliary live steam passing to chamber 2 is reduced by the throttling action of a suitable choke port 38.

From the above it will be evident that either exhaust steam or auxiliary live steam will be supplied to the injector at all times provided that 10 operating steam for the control mechanism described is supplied through pipe 9.

The admission of water to the injector is also controlled through this pipe, while the regulation of the amount of water supplied to the injector is 15 controlled through the manually operable handle 18.

Pipe 9 is supplied with steam from the boiler from pipe 39 in which is located the control valve 40. A second pipe 41, also controlled by valve 40, 20 supplies steam to the throttle valve of the driving element of pump F, which has been indicated as a centrifugal pump driven by a steam turbine. The turbine throttle comprises a conical valve member 42 axially movable to regulate the quantity 25 of steam admitted from pipe 41 to the inlet passage 43, said valve member being connected by a suitable linkage, indicated generally at 44, to a float 45 pivotally mounted in the lower part of the main chamber 46 of the tank D. The bottom 30 of chamber 46 is connected by means of conduit E with the suction side of pump F. Steam exhausted from the pump turbine passes through pipe 47, which has two branches 47a and 47b. Branch 47a has located therein a back pressure 35 relief valve 48 which may be set to produce any desired back pressure in the exhaust pipe 47, which if exceeded will cause valve 48 to open, thereby permitting the exhaust steam to pass to atmosphere through branch 47a.

40 Branch 47b leads to the top of the tank D and supplies steam, under a maximum pressure determined by the setting of valve 48, to a distributing member 49 from which the exhaust steam is directed into the tank through a plurality of 45 openings 50.

The delivery conduit C leading from the injector is preferably connected to a perforated discharge member 51 located directly under the member 49, member 51 serving to produce a fine spray of 50 water adapted to mingle with and condense the steam discharged through openings 50. The top of the tank may be made into a separate mixing chamber by means of a baffle 52 from which the water discharged from 51 and the condensed 55 steam from 49 may flow to the main chamber 46.

Assuming that it is desired to supply feed water to the boiler, operation of the apparatus is as follows: Valve 40 is opened, admitting steam to pipes 41 and 9. This causes the injector water valve 60 7 to be opened and also either the exhaust steam valve 29 or the automatic valve 22 to be opened so that the injector is supplied with water and either exhaust or auxiliary steam, depending upon whether or not the main engine is in operation. 65 The quantity of water delivered by the injector is manually regulated through handle 18 and the water so delivered by the injector passes through spray member 51 to the tank D. If, when the apparatus is started, no water is in the tank D, the 70 turbine throttle valve 42 is closed by the depression of float 45 and the admission of steam to pipe 41 will not cause the pump to operate. Continued operation of the injector will rapidly fill chamber 46, causing float 45 to rise and open valve 42 and thereby starting the pump after a

predetermined water level is reached in tank D. The speed of the pump F will be determined by the level of the water in chamber 46 until valve 42 is fully opened by rise of the water level in the chamber. Rise of the water level in chamber 46 5 beyond the point necessary to fully open valve 42 is prevented by making the maximum capacity of the pump greater than the maximum capacity of the injector, so that with valve 42 wide open the water level in chamber 46 will drop. Such drop 10 will cause the pump to slow down until it is automatically stabilized at a speed causing it to deliver to the boiler the same amount of water that is delivered to the tank by the injector, plus the condensate formed in the tank. 15

As soon as the pump turbine begins to operate, exhaust steam therefrom is delivered under pressure through the exhaust branch 47b to the mixing chamber above baffle 52 and the steam serves to raise the temperature of the water delivered by 20 the injector to a value above that possible to secure with exhaust steam from the main engine. Such a result is possible due to the fact that the pump turbine is operated against a relatively high 25 back pressure maintained by means of the relief valve 48, which may be of any suitable form.

The back pressure valve 48 also enables the turbine exhaust to maintain the surge tank under pressure, which is necessary in order to supply the pump with water under pressure. If the 30 suction side of the pump were supplied with hot water from the injector at or near atmospheric pressure, the pump would break its suction due to flashing of a certain amount of the suction 35 water into steam.

It will be apparent that the injector, pump and tank may be so proportioned that under normal operating conditions the entire exhaust from the pump turbine may be condensed in the heater D and therefore conserved, since the 40 heat from this steam is returned to the boiler in the feed water.

Under some operating conditions and with certain combinations of pump and injector units, it may happen that the exhaust from the pump is 45 insufficient to keep the pressure in tank D at the desired value. In order to insure a predetermined minimum pressure value in tank D, a supply of exhaust steam from some other steam-operated auxiliary, or live steam, may be admitted through the conduit 53. This may be termed auxiliary heating steam. If live steam is utilized, conduit 53 may be connected to pipe 41. Flow through conduit 53 is controlled by the regulating valve 54, which is diagrammatically illustrated as closed by pressure in tank D, acting through the pipe 55, which communicates with chamber 56 above the valve operating piston 57. Valve 54 is opened by spring 58. 55

Obviously, with this arrangement, valve 54 is 60 set so as to be closed by a lower pressure in tank D than is required to open the relief valve 48. It will thus be seen that the pressure in tank D may be held within a predetermined range, the minimum value of which is controlled by 65 valve 54 and the maximum value of which is controlled by valve 48. By adjustment of these valves, this pressure range may be altered as desired.

In Fig. 2, a modified arrangement is illustrated 70 in which the general organization is the same as that shown in Fig. 1, but in which the regulation of the amount of feed water supplied by the system is effected by manual control of the output of the pump, coupled with automatic regulation 75

of the quantity of water delivered by the injector in accordance with the rate of feed of the pump.

In this arrangement the injector A receives water from the supply conduit B and delivers it at elevated pressure through conduit C to the surge tank D. From the surge tank the water is withdrawn through conduit E by the pump F which delivers it to the boiler through conduit G. Steam for operating the pump and the injector is admitted through the supply pipes 39 and 9 and auxiliary live steam may be admitted to the surge tank through the pipe 53. The exhaust steam from the pump may also be maintained under a desired degree of back pressure by means of the valve 48 and delivered under such pressure through the pipe branch 47b.

The details of construction of the injector, pump and surge tank are advantageously the same as previously described in detail in conjunction with Fig. 1 and in the present embodiment are shown in elevation, corresponding parts being correspondingly designated.

The difference in construction represented by the present embodiment, as compared with that shown in Fig. 1, is that the pump throttle 42 is suitably connected by means of a control rod 60 to a manually operable regulating hand wheel or the like 61, preferably located adjacent to the live steam control valve 40.

30 The sliding nozzle 3 of the injector, which controls the amount of water delivered to and by the injector is connected by means of a linkage consisting of rods 62 and 63 and arm 64 (see Fig. 2a) to the lever attached to the float 45 in the surge tank D.

As will be readily understood, the general operation of the apparatus will be the same as that previously described in connection with Fig. 1 but in the present instance regulation of the amount of feed water supplied to the boiler is controlled through the manual regulation of the pump throttle valve 42. Depending upon the rate at which water is withdrawn from the surge tank by the pump F, the nozzle 3 of the injector 45 will be adjusted to automatically correlate the capacity of the injector to the rate of operation of the pump. With this arrangement in order to insure an adequate supply of water to the pump, the maximum capacity of the pump is 50 made less than the maximum capacity of the injector, so that the injector may at all times be capable of supplying all of the suction water required by the pump.

It will be understood of course that the pump 55 F should be provided with an overspeed governor, which may be of any of the usual conventional types, in order to prevent racing of the pump in the event that for any reason the action of the injector is interrupted for a period long 60 enough to cause the surge tank to be emptied by the pump.

From the foregoing description it will be evident that the embodiment of the invention diagrammatically illustrated herein by way of example may be widely varied without departing from the invention, the scope of which is defined in the appended claims.

I claim:

1. Means for supplying preheated feed water 70 to a boiler comprising an exhaust steam injector of the forcing type for delivering water under pressure and having means for regulating the amount of water supplied thereto, a steam driven pump having a throttle valve, a conduit for delivering water under pressure from the delivery

end of the injector to the suction end of the pump, manually controlled means for actuating said water regulating means and means for varying the opening of said throttle valve in accordance with variations in the rate at which water is supplied through said conduit by said injector. 5

2. Means for supplying preheated feed water to a boiler comprising an exhaust steam injector, of the forcing type for delivering water under pressure and a steam driven pump arranged in 10 series, with the injector delivering water to the pump at a pressure substantially above the pressure of the exhaust steam supplied to the injector, means comprising a part of the injector for determining the rate at which feed water is supplied 15 to the injector and means influenced by the rate at which feed water is supplied by the injector for governing the operation of the pump.

3. Means for supplying preheated feed water to a boiler comprising an exhaust steam injector, 20 means for regulating the amount of feed water supplied to said injector, a mechanically operated pump having a greater maximum capacity than the maximum capacity of the injector, means for conducting water delivered by said 25 injector to the suction end of said pump, and means for automatically regulating the rate at which said pump operates in accordance with the rate at which the injector delivers water to the pump. 30

4. Means for supplying preheated feed water to a boiler comprising an exhaust steam injector, of the forcing type, a steam driven pump, a conduit connecting the delivery end of the injector and the suction end of the pump, said conduit including apparatus for condensing steam with water passing through the conduit, and means for maintaining the pressure in said conduit at a pressure substantially above that of the exhaust steam supplied to the injector and for 40 further heating in said conduit the water delivered by the injector comprising means for conducting exhaust steam from the pump to said apparatus and means for conducting an auxiliary supply of steam to said apparatus when the quantity of exhaust steam from the pump is insufficient to maintain a desired pressure in said conduit. 45

5. Means for supplying preheated feed water to a boiler comprising an exhaust steam injector, 50 a steam driven pumping unit, means for conveying water delivered by said injector to the suction end of said pumping unit, said means including a surge tank, means for maintaining the exhaust steam from said pumping unit at a pressure substantially above atmospheric, means for conveying the exhaust steam from said pumping unit to said surge tank, and means controlled by the water level in said surge tank for controlling the operating rate of said pumping unit. 60

6. Means for supplying preheated feed water to a boiler comprising an exhaust steam injector, a steam driven pumping unit, a conduit including a surge tank for conveying water delivered by said injector to the suction end of said pump, 65 a conduit for conveying the exhaust steam from said pumping unit to said surge tank, a second conduit for conducting an auxiliary supply of heating steam to said surge tank, a valve in said second conduit responsive to pressure in said 70 tank for limiting the minimum pressure in said tank, and a relief valve for limiting the maximum pressure in said tank.

7. In a power plant having a boiler and a main engine, an exhaust steam injector of the 75

- forcing type, means for supplying feed water for the boiler to said injector, means for supplying exhaust steam from the engine to the injector, a boiler feed pump having greater maximum capacity than the maximum capacity of the injector, means providing a closed pressure conduit for delivering heated feed water under pressure from the injector to the pump, means for delivering feed water from the outlet of the pump to the boiler, means associated with said injector for regulating the amount of feed water supplied thereto, and means for controlling the rate of operation of said pump in response to variations in the amount of water delivered by said injector.
8. In a power plant having a boiler and a main engine, an exhaust steam injector of the forcing type, means for supplying feed water for the boiler to said injector, means for supplying exhaust steam from the engine to the injector, a steam driven boiler feed pump, means providing a closed pressure conduit for delivering heated feed water from the injector to the inlet of the pump, said injector being so constructed as to deliver water at a pressure substantially above the pressure of the exhaust steam from the engine, said conduit including means for condensing steam with water passing through the conduit, means for conducting exhaust steam from said pump to said conduit to be condensed therein, means for conducting an auxiliary supply of steam to said conduit to be condensed therein when the exhaust steam from the pump is insufficient to maintain the pressure in said conduit at a value substantially above that of the pressure of the exhaust steam supplied to the injector, and means for delivering feed water from the outlet of the pump to the boiler.
9. The method of supplying preheated feed water to the boiler of a power plant having a main engine and a boiler feed pump which consists in heating the boiler feed water by condensing therewith exhaust steam from the main engine, utilizing a part of the energy of the exhaust steam so condensed to elevate the pressure of the feed water to a value above that of the pressure of the exhaust steam, delivering the heated feed water to the boiler feed pump at elevated pressure, pumping the feed water to the boiler, and controlling the amount of water fed to the boiler by regulating the amount of water supplied to the pump due to the condensing action of the exhaust steam.
10. The method of supplying preheated feed water to the boiler of a power plant having an engine and a steam driven pump for the boiler which consists in heating the feed water by condensing therewith exhaust steam from the engine, utilizing a part of the energy of the exhaust steam so condensed to elevate the pressure of the feed water to a value above atmospheric but materially below boiler pressure, delivering said heated water under pressure to the pump, pumping the heated water to the boiler, utilizing the exhaust steam from the pump to heat the water at its elevated pressure before it is supplied to the pump and supplying auxiliary live steam to the water at its elevated pressure to heat it when the exhaust steam supply from the pump is inadequate.
11. The method of supplying preheated feed water to the boiler of a power plant having a main engine by the aid of an injector and a boiler feed pump, which comprises supplying the feed water to the injector, heating the feed water in the injector by condensing therewith exhaust steam from the main engine, utilizing a part of the energy of the exhaust steam so condensed to elevate the pressure of the feed water to a value above that of the pressure of the exhaust steam, delivering the heated feed water under pressure to the boiler feed pump, regulating the amount of feed water supplied to the injector in accordance with boiler needs, and controlling the rate of operation of the pump in accordance with the rate of operation of the injector.
12. The method of supplying preheated feed water to the boiler of a power plant having a main engine by the aid of an injector and a steam driven boiler feed pump, which comprises supplying the feed water to the injector, heating the feed water in the injector by condensing therewith exhaust steam from the main engine, utilizing a part of the energy of the exhaust steam so condensed to elevate the pressure of the feed water to a value above that of the pressure of the exhaust steam, delivering the heated feed water under pressure to the boiler feed pump, regulating the amount of feed water supplied to the injector in accordance with boiler needs, controlling the rate of operation of the injector, and condensing exhaust steam from the pump with the feed water after it is delivered from the injector and before it is supplied to the pump.
13. The method of supplying preheated feed water to the boiler of a power plant having a main engine and a boiler feed pump which consists in heating the boiler feed water by condensing therewith exhaust steam from the main engine, utilizing a substantial part of the energy of the exhaust steam so condensed to create a forcing jet whereby to elevate the pressure of the feed water to a value substantially above that of the pressure of the exhaust steam, delivering the heated feed water at elevated pressure to the boiler feed pump, thereafter pumping the feed water to the boiler, and regulating the amount of feed water pumped to the boiler by regulating the amount of water with which said exhaust steam from the main engine is condensed.
14. Apparatus for supplying preheated feed water to the boiler of a locomotive comprising a first forcing means consisting of a mechanical pump adapted to receive feed water at elevated pressure, a delivery conduit for conducting feed water from the pump to the boiler, a second forcing means consisting of an exhaust steam injector of the forcing type, means providing a connection for supplying to said pump feed water delivered from said injector, means for supplying exhaust steam from the locomotive engine to said injector for operation of the injector by exhaust steam when said engine is in operation, said injector delivering feed water preheated by the condensation of said steam at a pressure substantially above exhaust steam pressure but below boiler pressure, manually controllable means for regulating the rate at which water is delivered by one of said forcing means, and means for automatically correlating the rate at which water is delivered by the other of said forcing means to the rate of delivery of the forcing means which is manually controlled.
15. Apparatus for supplying preheated feed water to the boiler of a locomotive comprising a first forcing means consisting of a mechanical pump adapted to receive feed water at elevated pressure, a delivery conduit for conducting feed water from the pump to the boiler, a second forcing means consisting of an exhaust steam in-

jector of the forcing type, means providing a connection for supplying to said pump feed water delivered from said injector, means for supplying exhaust steam from the locomotive engine to said injector for operation of the injector by exhaust steam when said engine is in operation, said injector delivering feed water preheated by the condensation of said steam at a pressure substantially above exhaust steam pressure but below boiler pressure, manually controllable means for regulating the rate at which water is delivered by said exhaust steam injector, and means for automatically correlating the rate at which water is delivered by said pump to the rate of delivery of 15 said injector.

16. Apparatus for supplying preheated feed water to the boiler of a locomotive comprising a first forcing means consisting of a mechanical pump adapted to receive feed water at elevated 20 pressure, a delivery conduit for conducting feed water from the pump to the boiler, a second forcing means consisting of an exhaust steam injector of the forcing type, means providing a connection for supplying to said pump feed water 25 delivered from said injector, means for supplying exhaust steam from the locomotive engine to said injector for operation of the injector by exhaust steam when said engine is in operation, said injector delivering feed water preheated by the condensation of said steam at a pressure substantially above exhaust steam pressure but below boiler pressure, manually controllable means for regulating the rate at which water is delivered by said mechanical pump, and means for 30 automatically correlating the rate at which water 35

is delivered by said injector to the rate of delivery of said pump.

17. In a power plant having a boiler and a main engine, an exhaust steam injector of the forcing type, means for supplying feed water for 5 the boiler to said injector, means for supplying exhaust steam from the engine to the injector, a boiler feed pump having a maximum capacity less than the maximum capacity of the injector, means providing a closed pressure conduit for 10 delivering heated feed water under pressure from the injector to the pump, means for delivering feed water from the outlet of the pump to the boiler, means associated with said pump for regulating the amount of feed water delivered thereby 15 and means for controlling the rate of operation of said injector in response to variations in the amount of water delivered by said pump.

18. Means for supplying preheated feed water to a boiler comprising an exhaust steam injector, 20 means for regulating the amount of feed water supplied to said injector, a mechanically operated pump having a maximum capacity less than the maximum capacity of the injector, means for conducting water delivered by said injector to the suction end of said pump, means for conducting water delivered by said pump to the boiler, 25 manually controllable means for regulating the rate at which water is supplied to the boiler by said pump, and means for automatically regulating the rate at which said injector operates in accordance with the rate at which water is delivered by said pump.

NEAL T. MCKEE.
